(57) **CLAIM**

The ornamental design for a roadway luminaire, as shown and described.

DESCRIPTION

FIG. 1 is a bottom perspective view of a roadway luminaire, showing our new design;

FIG. 2 is a top perspective view thereof;

FIG. 3 is a top plan view thereof;

FIG. 4 is a bottom plan view thereof;

FIG. 5 is a left side view thereof;

FIG. 6 is a right side view thereof;

FIG. 7 is a front view thereof; and,

FIG. 8 is a rear view thereof.

The broken lines shown in the figures represent portions of the roadway luminaire that form no part of the claimed design.
